UNITED STATES PATENT OFFICE

146,697

DESIGN FOR A FOOD TRAY OR SIMILAR ARTICLE

Irven B. Bates, Los Angeles, Calif.

Application January 5, 1946, Serial No. 125,288

Term of patent 14 years

(Cl. D44—10)

To all whom it may concern:

Be it known that I, Irven B. Bates, a citizen of the United States and resident of the city of Los Angeles, county of Los Angeles, State of California, have invented a new, original, and ornamental Design for a Food Tray or Similar Article, of which the following is a specification, reference being had to the accompanying drawings, forming a part thereof, in which:

Fig. 1 is a perspective view of a food tray or similar article, showing my new design;

Fig. 2 is a top plan view;

Fig. 3 is a bottom plan view;

Fig. 4 is a front side view;

Fig. 5 is a back side view; and

Fig. 6 is an end view thereof.

I claim:

The ornamental design for a food tray or similar article, substantially as shown.

IRVEN B. BATES.
